UNITED STATES PATENT OFFICE

HOWARD E. BLOOD, OF DETROIT, MICHIGAN, ASSIGNOR TO NORGE CORPORATION, OF DETROIT, MICHIGAN, A CORPORATION OF MICHIGAN

WATER COOLER

Application filed October 4, 1930. Serial No. 486,316.

My invention relates to an improved water cooling arrangement particularly applicable to refrigerator cabinets.

The main feature of the invention resides in a water cooling tank immediately located within a refrigerator cabinet to be cooled and connected at its upper end with a supporting funnel opening to the exterior of the cabinet to receive and support a water bottle such as is commonly used in the retailing of drinking water to homes or offices, and the provision of a faucet at the lower end of the tank adapted to be adjusted so that cold water may be readily drawn from the tank and to be swung back within the refrigerator cabinet so that the cabinet doors may be closed.

Referring to the drawings,

Figure 1 is a front elevation of a refrigerator cabinet with part of the door broken away to show the water cooling installation and arrangement;

Figure 2 is an enlarged sectional view of a faucet which may be used.

On the drawings, 10 represents a refrigerator cabinet having the space 11 subdivided by shelving 12 and having in an upper corner the housing 13 surrounding the cooling coils and forming the freezing compartment.

My water cooling attachment comprises a tank 14 which may be of the rectangular shape shown or of any other desired shape. A conical holder or funnel 15 is provided for supporting the water supply container 16 which may be a bottle such as is commonly used in the retailing of drinking water to homes or offices. This holder has its bottle receiving mouth open to the exterior of the cabinet and may be entirely at the exterior of the cabinet or partly therein as shown at the top of Figure 1.

A suitable tube 17 connects the upper part of the tank 14 with the outlet of the funnel and the funnel is of such depth that the mouth of the bottle will be a distance above the outlet and away from the funnel sides. With this arrangement the flow of the water from the bottle through the tank would be governed by the height of the water in the funnel. As long as there is sufficient water

in the funnel to close the mouth of the bottle no water will flow therefrom, but when the water level drops below the bottle mouth water will flow until the bottle mouth is again closed.

As the water is cooled in the tank 14 it will tend to settle toward the bottom thereof and I provide a faucet 18 at the lower part of the tank. An efficient form of nozzle is shown in detail in Figure 2. It comprises the body 19 adapted to be screw threaded or otherwise secured to the tank and having the passage bore 20. A transverse bore 21 receives a valve 22 rotatable by a handle 23. Between the handle and the body 19 the inner end of the spout 24 receives the valve, the spout passageway being enlarged at its inner end to form the water receiving chamber 25 which is connected by ports 26 with the valve bore or passageway 27 which at its lower end has the cut-off port 28 adapted to connect the valve bore with the body passage 20 when the valve is in a certain position and in other positions to cut off the water flow. Suitable sealing washers 29 are inserted between the spout and the faucet body and handle and the spout may be swung laterally but with its bore at all times connected with the valve bore.

In the arrangement shown at the top of Figure 1, the bottle 16 is mounted in the holder 15 on top of the cabinet, and the tank 14 is mounted against the side of the freezing compartment 13 where it will be quickly cooled. The tank itself could form a side or baffle wall for the freezing compartment and will thus be in intimate contact with the freezing coil. The faucet may be at the front of the tank 14 as shown and normally its spout is swung to be within the refrigerator passage so that the doors 30 can be closed. When it is desired to draw water from the tank 14 the door is opened and the faucet is swung to extend forwardly so that a glass or other receptacle may be conveniently placed below the faucet and the valve is then opened by turning the handle 23. As soon as the level drops in the tank so that the mouth of the supply bottle will be exposed water will

flow from the bottle to refill the tank until its mouth is again closed by the water.

As shown at the right of Figure 1, the bottle holder or funnel may be located at the side of the cabinet and supported by a bracket 32 secured to the cabinet to receive its water supply from the bottle through a passage 34 which may extend through the bracket 32, and the faucet 34 will be at the bottom of the tank. It is evident that the supply bottle could be located at any convenient position outside of the cabinet and the tank located at any convenient position within the refrigerator below the level of the bottle mouth or in position so that the flow of water from the bottle will be automatically regulated by the cooperation of the water with the bottle mouth.

It is also evident that instead of being of swivel construction to be swung into or out of the cabinet, the faucet could be permanently outside of the cabinet so that the door need not be opened when it is desired to draw cold water. For example, the faucet could be on the outside on the side of the cabinet as indicated at 35' by dotted lines, or it could extend forwardly outside of the box between the cabinet side wall and the edge of the door, and the door could then be formed to clear the faucet during opening or closing thereof.

Although I have shown a practical and efficient embodiment of my invention I do not desire to be limited to the construction and arrangement shown and described as modifications and changes may be made without departing from the scope and spirit of the invention.

I claim as follows:

In combination with a refrigerator cabinet, a water tank within said cabinet, a funnel supported by the cabinet with its mouth in position to receive an inverted water supply bottle, said water tank being of narrow width and supported on edge at one side of the cabinet freezing compartment and with its front edge adjacent to the door of the cabinet, a connection between the funnel outlet and the upper part of said tank, and a faucet supported on the front edge of said tank at the bottom thereof, said faucet comprising a valve for controlling the outflow of water and a swiveled spout adapted to be normally swung inwardly to permit closure of the cabinet door and to be swung outwardly when the door is opened for discharge of water from the tank when the faucet valve is opened.

In testimony whereof I have hereunto subscribed my name at Detroit, Wayne County, Michigan.

HOWARD E. BLOOD.
